UNITED STATES PATENT OFFICE.

CHARLES C. WILLIAMS, OF COLUMBUS, OHIO.

MECHANISM FOR OPERATING RAILWAY-SWITCHES.

SPECIFICATION forming part of Letters Patent No. 251,983, dated January 3, 1882.

Application filed August 30, 1881. (No model.)

To all whom it may concern:

Be it known that I, CHARLES C. WILLIAMS, of Columbus, in the county of Franklin and State of Ohio, have invented certain new and useful Improvements in Mechanism for Operating Railway-Switches, of which the following is a specification.

My invention relates to improvements in railway-switches of the class in which the switches, 10 if open or improperly adjusted, are actuated or closed by the passage of the engines along the rails, as they approach the switches; and my invention especially pertains to improvements in that type of such class of automatically- 15 actuated switches in which rollers mounted on the engines are caused to act upon the switches through or by way of tread-bars or levers at the sides of or between the rails of the track.

20 My improvements consist in a novel organization of parts and in certain combinations of devices, hereinafter designated by the claims, whereby the switches, if open, may with certainty be closed or set by an attachment to the 25 engine passing along the rails. The organization is such that the switch may be operated by the attendants or trackmen independently of the passage of an engine over the road, and is also such that the roller on the engine successively acts upon the tread-bars to unlock 30 and then set the switch.

The accompanying drawings show a suitable embodiment of devices for carrying out my invention as applied to the main line, or so as to be operated by engines passing along the main line only. Obviously the sidings or rails of branch tracks may be fitted with mechanism so that switches may be actuated from them as well as from the main line.

40 Figure 1 is a plan or top view. Fig. 2 is a transverse section on the lines 22 of Figs. 1 and 6. Fig. 3 is a vertical longitudinal section on the line 3 3 of Fig. 4, showing a portion of the engine and the roller thereof as about to act upon the tread-bars. Fig. 4 is a vertical transverse section on the line 4 4 of Fig. 3. Fig. 5 is a view, partly in plan and partly in horizontal section, on the line 5 5 of Fig. 6; and Fig. 6, a view, partly in elevation and partly in ver-

tical longitudinal section, on the line 6 6 of 50 Fig. 5.

The rails A A and A' A' of the main line and the rails B B of the siding, branch line, or turn-out are suitably constructed and arranged relatively to each other and to the switch proper 55 or movable section of track composed of the rails a a. The rails of this switch-section of the track are pivoted or suitably jointed at or near the points b b, or so as to be capable of adjustment in line either with the main rails 60 A A and A' A' or with main rails A A and siding-rails B B.

Two sets of pivoted tread-bars or long levers with inclined or cammed surfaces are mounted in pairs, C D, C' D', between the main rails at 65 either side of the switch. The two inclined surfaced levers of each pair are pivoted independently, or so as to vibrate vertically without the one interfering with or affecting the other. The levers C C', I term "unlocking" 70 or "releasing" levers, and the levers D D' "throwing" or "setting" levers, a releasing and a setting lever constituting a pair, as above indicated.

The releasing-levers C C' project farther from 75 the switch at their ends most remote therefrom than do the setting-levers at their corresponding ends. At their ends nearest the switch the levers of each pair are jointed to a cross-tie or other support between the rails. 80 In this instance a single pivot, b, serves to joint the levers C D to lugs secured to a cross-tie, and the pair of tread-bars C' D' are similarly jointed to a tie by a common pivot, f. The switch-unlocking levers are thus made 85 longer than the throwing-levers.

The cams or inclines c c' of the releasing-levers C C' extend farther beyond or more remote from the switch than do the inclines d d' of the setting-levers or tread-bars D D'. The inclines c c' are respectively located near to and so as to partially lap or extend along by the sides of the respective inclines d d' of the levers D D', for a purpose hereinafter to be explained.

The outer or free ends of the levers C C' have jointed connection respectively with the cranks of rock-shafts E. Links e e serve to

flexibly connect the levers and the cranks F of the outer ends of these rock-shafts. The rock-shafts E are suitably housed and mounted in bearings beneath and at the side of the track, 5 and at their inner ends are provided with cranks f', which have connection by rods G G' with an adjustable detent or switch locking and releasing device, presently to be described, located at the side of the track close to the 10 switch, as usual.

The switch-setting tread-bars D D' at their outer ends are linked to cranks h of rock-shafts H, similar to those, E, above described. Connecting-rods I I' are pivoted at their outer 15 ends to cranks i of the rock-shafts H, and their opposite ends have connection with an endwise-moving operating-rod or throw-bar, J, of the switch. The connecting-rods G G' and I I' are covered or protected by a housing, G² G².

The drawings show one only of each of the above-referred-to pairs of rock-shafts E, links e e, cranks F and f', rock-shafts H, and cranks h and i; but as the omitted parts are exact 25 duplicates of those shown, illustration of both sets of devices is unnecessary to a full understanding of my improvements.

The mechanism for locking, releasing, and setting the switch, and with which the rods 30 G G', I I' connect, as in this instance shown, is as follows:

The detent with which the rods G G' connect consists of a cross-head or horizontally-sliding plate, K, reciprocating in suitable 35 guideways, j j, and provided with two notches, k k', for engagement with a lug or tooth, j', on the throw-bar J, which slides endwise in guides or bearings J' J'. The sliding detent K is connected by a perforated stirrup or yoke, l, with 40 the rod G. This connecting-rod is passed through the perforation in the yoke, and its withdrawal is prevented by a cross pin or nut. A spiral spring, L, is coiled around the rod G between the yoke and a perforated support or 45 guiding-lug, l', through which the rod passes near the yoke of the detent. This spring bears at its opposite ends against the lug and detent-yoke, and acts always with a tendency to move the detent inward or toward the throw-bar, or to hold it up to said bar. The connection between the rod G' and the detent K is 50 made by a rock-shaft, M, provided with a crank, m, to which the connecting-rod is pivoted, and also having a crank or wiper, m', bearing 55 against the yoke of the detent. The rock-shaft M projects through the side of and is supported at one end in the housing or protecting-easing N of the switch-controlling mechanism, and at its opposite end is mounted in 60 a bearing-post, n, secured to the base of the housing. A lever, M', preferably a foot-lever or treadle, is fastened to the end of the rock-shaft M outside of the housing, so that a person may unlock the switch by the action of 65 his foot and throw or set it by a hand-lever, as farther on explained.

The rods I I', which connect with the setting tread-bars D D', are respectively connected at their inner ends by pivots with the respective ends of a horizontal arm or cross-bar, O, 70 projecting in opposite directions from an upright shaft, O'. This shaft, by its movements and connections, serves to operate the switch throw-bar. It is supported at its lower end in the base of the housing N, and is sustained 75 above said housing, so that it may be turned about a vertical axis by a bearing in a plate, O², supported by legs resting on the bottom of the housing. A lever, N', is secured to the vertical shaft above and close to its upper 80 bearing. This hand-lever N' and the foot-lever M' are so arranged relatively to each other that a person may advantageously operate the switch-releasing devices with his foot and immediately after throw the switch by the hand-lever without having to lose time by changing his position or grasping first one and then another lever.

The shaft O' carries a curved or segmental rack, P, near its lower end, which rack engages with a rack-bar or series of teeth, p, arranged upon the side of the throw-bar J contiguous to the segmental rack.

It will readily be understood that the throw-bar of the switch may be adjusted by the turning of the shaft O', whether the detent K be operated by foot or by hand or automatically by an engine on the track, as presently to be described, so as to withdraw the notch k or k' from engagement with the lug j' of the throw-bar.

A vertically-adjustable roller, Q, with a broad tread or bearing surface, is mounted upon or close to the pilot or cow-catcher of an engine. The roller is supported by a shaft mounted at its ends in lugs at the lower end of a sliding frame or cross-head, R, reciprocated vertically in guideways q q by a lever, S, and suitable connections. The lever is preferably placed under the control of the engineer by suitable 110 and obvious devices.

As shown, the lever S is provided with a spring-detent, s, to engage with one or other of the notches in a rack, T, according to whether the roller is adjusted in its lowermost and operative position or in its elevated position, so as to be out of action.

A connecting-rod, S', is jointed at its opposite ends with the controlling-lever and with one end of a bell-crank or elbow lever, t, on a rock-shaft, T', supported in suitable bearings. The opposite end of the elbow-lever is jointed to a post or arm, r, of the roller-supporting cross-head, R.

With the tread-bar-actuating roller Q adjusted and locked in its operative position, it will be seen that when the engine comes to the tread-bar O (or to the tread-bar O', if approaching the switch from the opposite direction) the roller first depresses the switch-unlocking tread-bar. This tread-bar, through its connections with the throw-bar detent, releases the

switch. Before the roller leaves the incline of the releasing tread-bar it passes upon the incline of the switch-setting tread-bar, and by depressing this bar operates the switch-adjusting devices through the connections between the tread-bar and throw-bar of the switch. The inclines of the switch-releasing levers or tread-bars must be long enough and project sufficiently far beyond the inclines of the switch-throwing levers to give ample time for fully releasing or unlocking the switch before the action of the roller upon the incline of a throwing-lever. These inclines are also made quite gradual and of ample length to gradually operate the switch, so as to avoid a too quick action or violent strain upon the mechanism. The switch, having been set for the passage of the engine or train over the main line, is left undisturbed by the travel over the pair of tread-bars at the opposite side of the switch, as both of the switch-setting tread-bars are locked in their depressed position by the action of the spring of the detent K, and the depression of a releasing tread-bar has no effect upon the switch.

I do not broadly claim the combination of a switch and controlling mechanism thereof actuated by connections with yielding tread-bars or pivoted levers which are operated by rollers or other attachments of cars or engines in their passage along the track, as I am aware that various combinations of devices have been devised for this purpose. Neither do I wish to be understood as confining my invention strictly to details of construction or precise arrangements of parts in all respects as illustrated in the drawings and hereinbefore specifically described, as parts embodied in my improvements may be modified in various ways without departure from my invention, and essential and co-operating features less than the whole organization of parts may advantageously be used under some circumstances.

As obvious modifications of my improvements may be mentioned the jointing of both connecting-rods G G' with the rock-shaft M, instead of connecting one of the rods with the detent K, the substitution for the spring L around one of these rods of an independently 50 and suitably mounted spring acting on the detent, or the employment of a weight to perform the function of the spring, and the tread-bars, instead of being placed in the middles of the tracks, may be arranged closer to or at 55 either side of either rail of a track, as may be deemed preferable, the tread-bar-actuating rollers being properly adjusted to suit such changes in the positions of the tread-bars.

I claim as of my own invention—

60 1. The combination of the main-line rails, the switch, the releasing-lever pivoted at its end next the switch, the setting-lever close to the releasing-lever and correspondingly pivoted, the inclines of said levers arranged with 65 the incline of the releasing-lever extending at its outer end farther from the switch than does

the corresponding end of the incline of the setting-lever, and with the inner end of the setting-lever incline extending nearer to the switch than does the corresponding end of the releasing-lever incline, the rock-shafts to which the said levers are connected, and the switch locking, releasing, and setting mechanism, with which mechanism said rock-shafts are connected, substantially as and for the purpose hereinbefore set forth. 70 75

2. The combination of the rails, the switch, the tread-bars on opposite sides of the switch, and the mechanism connecting the tread-bars with the switch, the said bars being provided with inclines and arranged in two sets or pairs pivoted at their ends next the switch, each pair consisting of a switch-releasing and a switch-setting bar, with the incline of the releasing bar extending partly beyond and partly by the side of and close to the incline of the setting-bar, and with the setting-bar incline extending nearer the switch than does the releasing-bar incline, substantially as and for the purpose hereinbefore set forth. 80 85 90

3. The combination of the switch-releasing tread-bars C C', the switch-setting tread-bars D D', their pivots b' f, the inclines c c', d d', arranged relatively to each other and to the switch as described, the rock-shafts E H, and the rods connecting said rock-shafts with the locking, releasing, and setting devices by the side of the switch, substantially as and for the purpose hereinbefore set forth. 95

4. The combination of the switch throw-bar, the turning shaft O', the rack thereon, the rack-bar on the throw-bar, the rock-shaft M, the detent engaging with the throw-bar and actuated by the rock-shaft, and the spring acting on the detent, substantially as and for the purpose hereinbefore set forth. 100 105

5. The combination, substantially as hereinbefore set forth, of the switch, the throw-bar, the upright shaft, the gearing connecting said shaft and the throw-bar, the hand-lever secured to said shaft, the spring-detent engaging with the throw-bar, the rock-shaft operating the detent, and the treadle or foot-lever secured to the rock-shaft, for the purpose described. 110 115

6. The combination of the switch-releasing tread-bars, the rock-shafts E, connected with said tread-bars, the switch-setting tread-bars, the rock-shafts H, with which they are connected, the switch throw-bar, the upright shaft geared therewith, the rods connecting said upright shaft with the rock-shafts H, actuated by the switch-setting bars, the spring-detent engaging with the throw-bar, the rock-shaft M, connected with the detent, and the rods connecting said rock-shaft and detent with the rock-shafts E, actuated by the switch-releasing tread-bars, substantially as and for the purpose hereinbefore set forth. 120 125 130

7. The combination of the single broad tread-roller Q, mounted upon the engine, and the tread-bars arranged in two sets or pairs

and located between the main rails, each of said pairs consisting of a switch-releasing and a switch-setting tread-bar, pivoted at their ends next the switch and provided with inclines, the inner end of the releasing tread-bar incline and the outer end of the setting tread-bar incline being arranged side by side and close together, and the opposite ends of said inclines projecting respectively away from

and toward the switch, substantially as and for the purpose hereinbefore set forth.

In testimony whereof I have hereunto subscribed my name.

CHARLES C. WILLIAMS.
